UNITED STATES PATENT OFFICE

ROBERT A. DORRILL, OF LITTLE SILVER, NEW JERSEY

GARMENT HANGER

Application filed December 3, 1930. Serial No. 499,615.

This invention relates in general to garment hangers, and particularly to hangers for supporting both garments having shoulder portions such as coats, and garments such as trousers, skirts, and the like.

Known garment hangers of this character are constructed so that when for example a coat and trousers are mounted on the hanger, the coat overlies or partially covers the trousers, and in removing the trousers from or placing them upon the hanger the coat is a hindrance and often is unintentionally displaced upon or pulled from the hanger. This is particularly annoying and is inevitable because in disrobing the coat is usually removed from the body and placed on the hanger first, while when dressing the trousers are usually first removed from the hanger.

One object of my invention is to provide a garment hanger embodying novel and improved features of construction to overcome the above described disadvantages of known garment hangers and admit of a coat or the like and trousers or the like to be easily applied to and removed from the hanger in the order in which such garments are usually divested and donned by the wearer without interference of one garment with the other.

Another object is to provide such a garment hanger having a main portion shaped to receive a shouldered garment, such as a coat, and another portion to receive a trousers or the like, said trousers-supporting portion being disposed out of or offset from the plane of the coat-receiving portion so as to be fully exposed and easily accessible at all times, and whereby a trousers hung thereon shall be disposed entirely outside and free from a coat on the hanger.

Other objects are to provide a garment hanger of this character including a main portion shaped to receive the shoulder portions of a coat or the like and to be suspended in a vertical plane, and a portion for supporting a trousers or the like disposed at substantially right angles to said shoulder-receiving portion and including a bar offset or spaced from the plane of said shoulder-receiving portion so as to permit the front edges of a coat to be arranged between said

bar and said shoulder-receiving portion, whereby said bar is fully exposed and easily accessible at all times; to provide such a garment hanger having said trousers-supporting portion separably connected to said main portion for convenience in packing of the hanger, and to obtain other advantages and results as will be brought out by the following description.

Referring to the accompanying drawing, in which corresponding and like parts are designated throughout the several views by the same reference characters,

Figure 1 is a front elevation of a garment hanger embodying my invention and showing the manner of suspending garments thereon;

Figure 2 is a top plan view of the hanger;

Figure 3 is a front elevation of a modified form of the invention;

Figure 4 is a horizontal sectional view, on the line 4—4 of Figure 3;

Figure 5 is an enlarged transverse vertical sectional view, on the line 5—5 of Figure 3, and

Figure 6 is a detached perspective view of the auxiliary trousers-supporting portion of the hanger shown in Figures 3 and 4.

Specifically describing the embodiment of the invention illustrated in Figures 1 and 2, the hanger comprises one piece of wire or the like which is bent to form a main portion A to receive the shoulders of a shouldered garment, such as a coat, and an auxiliary portion B to receive garments such as trousers, skirts and the like. The main portion includes a suspending hook 1 at opposite sides of which and extending in opposite directions in the same plane are shoulder-receiving parts 2. The auxiliary portion B comprises a trousers-supporting bar 3 and supporting arms 4 which are disposed approximately parallel to the bar 3 and extend inwardly in spaced relation thereto and are connected to the ends of the shoulder-receiving parts 2 by tie-bar portions 5 disposed substantially in the plane of the shoulder-receiving parts 2. When the hanger is suspended by the hook 1, the main portion A is arranged in substantially a vertical plane, and the trousers-

supporting bar 3 is spaced or offset horizontally from the shoulder-receiving parts so that the front edges of a coat or the like may be arranged in the spaces 6 between the garment-supporting bar and the main portion A, as clearly shown in Figure 2 of the drawing. The portions 7 of the supporting arms 4 serve as clamps for holding trousers or the like upon the trousers-supporting bar 3, and the trousers are applied to said bar by slipping one end upwardly between the supporting arms 4 and the bar 3 and draping the garment over the bar.

With this construction, when a coat or the like is placed upon the main portion A, and a trousers or the like is placed upon the trousers-supporting bar 3, the trousers are entirely exposed and fully accessible so that they can be removed from the hanger without hindrance by the coat and without disturbing the coat. Similarly, after the coat has been applied to the hanger the trousers may be easily applied to the garment-supporting bar without interference from the coat.

Preferably a second trousers-supporting bar 8 is suspended from the tie-bar portions 5 in substantially the plane of the shoulder-receiving parts 2, so that the hanger is capable of supporting two trousers, if desired.

Another form of the invention is shown in Figures 3 to 6, inclusive, wherein the hanger includes a suspending hook 9 and shoulder-receiving parts 10 arranged in the same plane at opposite sides of the hook 9 and preferably formed of wire. The ends of the shoulder-receiving parts 10 are connected by a tie-bar 11, which may be of any suitable material, such as wood. An auxiliary trousers-supporting portion is mounted upon the tie-bar 11, said auxiliary portion comprising a single length of wire or the like 12 having its end portions 13 returned inwardly in spaced relation to the middle portion, as at 14, to form a trousers-supporting bar 15, said end portions being then bent at 16 at substantially right angles to the bar 15 and in the same general plane. The extremities 17 of the end portions are bent at substantially right angles to said general plane to removably fit vertical openings 18 spaced longitudinally of the tie-bar 11 at its middle portion. When the hanger is suspended by the hook 9, the shoulder-receiving parts 10 and the tie-bar 11 are disposed in a substantially vertical plane, while the auxiliary portion is disposed in a substantially horizontal plane with the garment-supporting bar 15 horizontally spaced from the plane of the shoulder-receiving parts so that the front edges of a coat or the like hung upon the shoulder-receiving parts 10 may be arranged between the garment-supporting bar 15 and the tie-bar 11. This construction is in general the same as

that shown in Figures 1 and 2, the main difference being that the auxiliary portion is removable from the main portion by slipping the extremities 17 from the openings 18 in the tie-bar 11; and the garments may be applied to this form of hanger in the same manner as they are applied to the hanger shown in Figures 1 and 2.

If desired, a second trousers-supporting bar 19 may be suspended from the tie-bar 11 in substantially the same plane, and a spring-clamping arm 20 may be attached to the tie-bar to overlie the trousers-supporting bar 19 for clamping the trousers or the like upon said bar. Obviously, in applying the trousers to this bar, one end will be slipped between the clamp 20 and the bar 19 and between the bar 19 and the tie-bar 11 so as to drape the garment over the bar 19.

With my invention it will be observed that for example a coat and a trousers may be applied to and removed from the hanger in the order in which they are divested or donned by the wearer, respectively, and that neither of the garments interferes with the other upon the hanger.

While I have shown and described the invention as embodied in certain specific details of construction, it should be understood that this is primarily for the purpose of illustrating the principles of the invention, and that modifications and changes may be made in the details of construction, by those skilled in the art, without departing from the spirit or scope of the invention.

Having thus described the invention, what I claim is:

1. A garment hanger comprising a main portion including suspending means and parts extending in opposite directions at opposite sides of said suspending means and in a common vertical plane when the hanger is suspended, said parts being shaped to receive the shoulders of a coat or the like, the ends of said shoulder-receiving parts having tie-bar portions substantially in the plane of said shoulder-receiving parts, and an auxiliary portion including a trousers-supporting bar and horizontal supporting arms therefor extending inwardly from the ends of said trousers-supporting bar in spaced relation thereto and connected to said tie-bar portions, whereby said trousers-supporting bar is horizontally spaced from the plane of said main portion so that the edges of a coat or the like mounted on said shoulder-receiving parts may be arranged between said tie-bar portions and said trousers-supporting bar.

2. A garment hanger comprising a main portion including suspending means and parts extending in opposite directions at opposite sides of said suspending means and in a common vertical plane when the hanger is suspended, said parts being shaped to re-

ceive the shoulders of a coat or the like, the ends of said shoulder-receiving parts being connected together by a horizontal tie-bar in the plane of said shoulder-receiving parts, and an auxiliary portion including a trousers-supporting bar formed of a length of wire having its end portions returned inwardly in spaced relation to the middle portion and connected to said tie-bar so that said trousers-supporting bar is mounted on said main portion and horizontally spaced from the plane thereof.

3. A garment hanger comprising a main portion including suspending means and parts extending in opposite directions at opposite sides of said suspending means and in a common vertical plane when the hanger is suspended, said parts being shaped to receive the shoulders of a coat or the like, the ends of said shoulder-receiving parts being connected together by a horizontal tie-bar in the plane of said shoulder-receiving parts having vertical openings at its middle portion, and an auxiliary portion including a trousers-supporting bar formed of a length of wire having its end portions returned inwardly in spaced relation to the middle portion and its extremities bent at right angles to the plane of said middle portion and end portions and inserted in said vertical openings of the tie-bar so that said trousers-supporting bar is mounted on said main portion of the hanger and horizontally spaced from the plane thereof, whereby the front of a coat or the like on said main portion may be arranged between the ends of said trousers-supporting bar and said main portion.
